(57) **CLAIM**

The ornamental design for a stand-up pouch with air-filled hand-hold, as shown and described.

DESCRIPTION

FIG. 1 is a left side elevational view of the unfilled stand-up pouch with air-filled hand-hold showing our design, with the right side being a mirror image thereof;

FIG. 2 is a front and left side perspective view thereof in filled condition;

FIG. 3 is a top plan view thereof;

FIG. 4 is bottom plan view thereof;

FIG. 5 is a top view thereof, in filled condition;

FIG. 6 is a bottom view thereof, in filled condition;

FIG. 7 is a left side elevational view of the unfilled stand-up pouch with air-filled hand-hold, with the right side being a mirror image thereof;

FIG. 8 is a front and left side perspective view thereof, in filled condition;

FIG. 9 is a top plan view thereof;

FIG. 10 is bottom plan view thereof;

FIG. 11 is a top view thereof, in filled condition; and,

FIG. 12 is a bottom view thereof in filled condition.
